UNITED STATES PATENT OFFICE

HARRIE THOMPSON NOWOTNY, OF ST. LOUIS, MISSOURI.

SASH-HANGER.

1,279,749.

Specification of Letters Patent. Patented Sept. 24, 1918.

Application filed November 1, 1916. Serial No. 128,970.

To all whom it may concern:

Be it known that I, HARRIE THOMPSON Nowotny, a citizen of the United States, residing in the city of St. Louis and State of Missouri, have invented certain new and useful Improvements in Sash-Hangers, of which the following is a specification.

My invention relates to improvements in hangers for window sash, screens, etc., and more particularly to a hanger of this character which will also form a corner reinforcement for the sash.

The objects of the invention are to produce a device of extremely inexpensive and simple construction which can be stamped from one integral piece of metal and will form both a corner reinforcement and a hook hanger, the hook being formed by continuation of the corner reinforcement, which is bent laterally upon itself and is solid throughout, not being weakened at any point by cuts, indentations, or slots.

The above and other objects, I accomplish as hereinafter set forth, and as particularly pointed out in the appended claims, reference being had to the accompanying drawings in which adaptations or embodiments of my improved hanger are shown.

In the drawings:

Fig. 1 represents a side elevation of a fragment of a dwelling with a window casing or frame, window sash in said casing or frame, and a screen hung or suspended in said casing or frame by my improved hanger.

Fig. 2 is a fragmentary section on line 2—2, Fig. 1 illustrating a screen hung by my improved hook and also illustrating by dotted lines the oblique hanging position the sash would assume if the bottom shoulder of the casing were removed.

Fig. 3 is a fragmentary horizontal section taken on line 3—3, Fig. 1, through a window casing and sash with a screen hung therein by my improved hanger.

Fig. 4 is a corner fragment of a sash or screen frame in perspective, illustrating one form of my improved combined hanger and corner reinforcement fitted thereon.

Fig. 5 is a separate detached view of another form of my improved hanger.

Fig. 6 is a flat face view of the blank from which the form of my improved hanger shown in Fig. 5 is made, with the various

parts cut and shaped preparatory to being bent to form my improved device.

In referring to the embodiments or adaptations of my invention shown in detail in the accompanying drawings, like numerals designate corresponding parts.

My improved hanger is designed as an inexpensive but highly efficient article for suspending screens and the like in proper position in a window casing or frame, and it is so formed or constructed that it constitutes both a hanger and a corner reinforcement or brace.

In Figs. 1, 2, and 3, I have shown my improved hangers properly fitted on the upper two corners of a screen frame and hung in place in a conventional form of window, a portion of the wall of the dwelling being depicted in Fig. 1.

As illustrated, the usual and well known parts shown in Figs. 1, 2, and 3, comprise a window casing or frame, 1, window sash, 2, slidably fitted in said casing or frame, and the wall, 3, of the dwelling.

Besides a screen of the usual construction is shown in Figs. 1, 2, and 3, suspended in front of the lower sash by a pair of my improved hangers.

In hanging the screen, two pins, 6, are driven into the casing on opposite sides thereof and horizontally opposite each other and have their headed outer extremities projecting toward each other, as shown in Fig. 1. The projecting positions of these pins serve as supporting or sustaining parts, upon which the hangers are suspended as shown particularly in Figs. 1 and 2.

The improved hanger is preferably constructed as shown in Figs. 4, 5, and 6, being angular in form and having a portion, 7, which when the hanger is properly attached to a sash or screen extends vertically and another portion, 8, which extends horizontally and laterally from one side of the upper extremity of the vertical portion and at approximately a right angle to the horizontal portion. A continuation of the portion, 7, also extends above the juncture point of the horizontal portion, 8, and constitutes the hook proper being bent upon itself into the overhanging hook shown in Figs. 2, 4, and 5. Preferably, I bend the hook portion at three points, first giving a right angle bend at its juncture or merging point with the vertical

portion, 7, as indicated at 9, which forms the horizontal top portion, 10, of the hook proper, then giving a second bend, 11, obliquely outward and downward at the 5 outer termination of the horizontal top portion to form an outwardly flaring lip, 12, and finally bending the outer portion of said lip slightly upward at an intermediate point, 13, as shown in Figs. 2, 4, and 5, therefore 10 by imparting a slight angular form to the flaring lip, 12, and providing a wider spread of hook.

I may also form the hanger with an angle reinforcement, 14, which is bent at a right 15 angle to and extends longitudinally with the horizontal portion, 8, and is adapted to extend beneath and be fastened to the filler strip, 15, and a transverse vertical wall or closure, 16, which closes the inner end of the 20 opening through the hook as shown in Fig. 5.

This form of my improved hanger is shown in Figs. 5 and 6, and forms a stiffer, stronger and better fastened hanger than the 25 simpler form previously described.

It can be fastened to both the bottom surface and the end of the filler strip, suitable 30 openings, 17, being provided in the reinforcement, 14, and the wall or closure, 16, for nails, screws, or other fasteners, see Figs. 5 and 6. The wall or closure, 16, is 35 preferably formed by cutting the inner portion of the reinforcement by a transverse slit, 18, thus truncating its inner end and then also slitting the cut portion on the longitudinal line, 19, which occurs at the bend joining the portions, 8 and 14, and then extends in longitudinal alinement with the said 40 bend and terminates at the juncture point with the vertical portion, 7. The slotted fragment which is thus severed from both 45 the reinforcement, 14, and the portion, 8, is bent on a vertical line toward the hook and constitutes the wall or closure, 16, as shown in Fig. 5.

My improved hanger is extremely simple and inexpensive to manufacture, being formed of one integral piece of metal and so that it can be easily stamped out.

50 It forms both a supporting hook for the screen and a corner reinforcement, therefore combining in itself a hanger and reinforcement, so that not only will it support the screen but also strengthen and stiffen 55 the screen frame at its weakest point, that is the corner or juncture points of the portions or members of the screen.

While my improved hanger is chiefly designed as a screen or sash hanger, it is 60 equally adapted to and may be used for a variety of other purposes.

As shown, the hook proper is positioned on the inner side of the frame of the screen or sash, being offset therefrom and the angle 65 portions, 7, and 8, which constitute the rein-

forcement are fastened upon the inner surfaces of the horizontal and vertical portions of the sash or screen frame and extend in longitudinal alinement therewith respectively.

The hooks are arranged in pairs, being fastened one to each of the two upper corners of the frame and are adapted to be fitted upon and to catch over the projecting portions of the sustaining and positioning pins as shown in Fig. 1.

Owing to the offset position of the hooks, the screen or sash frame would naturally sway or swing inwardly when hung, and assume approximately the position shown in Fig. 2, in dotted lines, were it not that the lower end of the screen frame strikes or abuts against the shoulder at the bottom of the casing or window frame. This insures a tight connection at all points as the screen frame naturally falls inwardly by gravity.

The hook, it will be observed, is formed by bending a continuation of the angle reinforcement upon itself in a lateral direction, thereby providing a hook formation, which is offset, or bent, to one side from the flat angular reinforcement.

Further, the hook is solid, and has approximately the same width throughout, that is, it is equal in width to the reinforcement and is not cut, indented, slotted, or otherwise weakened at any point.

Owing to the comparative thinness of the metal from which the hook is bent, it partakes more or less of the nature of a spring and thus yields infinitesimally as it is hung in place thereby securing a snug and tight fit for the screen in the window casing.

While I have described in the foregoing specification adaptations or embodiments of my invention, it should be understood that the structural parts thereof may be varied, changed, modified or altered or one or more may be omitted or dispensed with without departing from the spirit of my invention, as fairly defined in the following claims, or as may be imparted thereto by invoking the doctrine of equivalents.

What I claim as my invention and desire to protect by Letters Patent is:—

1. A sash hinge embodying a flat vertical strip for attachment to the inner face of the vertical side bar of the sash frame, the upper end being bent forwardly and downwardly to form a hook for engaging a pin located in the window casing; a horizontal strip, right angled in cross section, extending at a right angle from said vertical strip, the lower rib thereof being adapted for engagement with the inner face of the horizontal top bar of the sash frame while the upper rib is adapted for engagement with a weather strip fastened to said top bar; and an ear, cut from the body portion ex-

cept on the side next the vertical strip aforesaid, and bent down from that side athwart the hook aforesaid, so as to form an end stop and fastening for said weather strip.

5 2. A sash hinge embodying a downwardly extending strip, having its upper end bent forward to form a hook; a laterally extending rigidly connected, auxiliary strip, bent upon itself at a right angle along its longi-

tudinal center line; and a stop, rigidly connected with the top of the hook at the inner edge thereof, and extending down across that side of the hook, substantially as shown. 10
